UNITED STATES PATENT OFFICE

FREDERICK H. WAGNER, OF BALTIMORE, MARYLAND, ASSIGNOR TO THE BARTLETT HAYWARD COMPANY, OF BALTIMORE, MARYLAND, A CORPORATION OF MARYLAND

CENTRIFUGAL DUST ARRESTER

Application filed April 25, 1929. Serial No. 358,068.

My invention relates to dust arresters of the centrifugal type such as are commonly employed in removing dust from air or gas.

Among the objects of my invention are the provision of an arrester which will function more effectively than the devices of the prior art, and one which will operate with very small expenditure of power.

Other objects of my invention will appear from the following description when read in connection with the accompanying drawings, in which:

Figure 1 is a vertical sectional view of one form of arrester embodying my invention, parts being broken away to show the interior structure;

Figure 2 is a sectional view showing further details of the interior structure;

Figure 3 is a section on line 3—3 of Figure 2;

Figure 4 is a section on line 4—4 of Figure 2;

Figure 5 is a section on line 5—5 of Fig. 2; and

Figure 6 is a sectional view on line 6—6 of Fig. 3.

The device as shown in Figure 1 comprises an upright cylindrical casing 7 partially closed at the top by a flaring cap 8 which merges into an outlet tube 9. The bottom of the casing is formed as a hopper 10 and is closed by a conical closure 11 attached to an arm 12. This arm is pivoted on a bracket 13 and the closure is normally biased to closed position by an adjustable weight 14. The hopper 10 forms a dust collecting receptacle from which the dust may be removed by opening the closure 11.

Suitably secured within and near the top of casing 7 is a flat plate 15 carrying suspended therefrom a cylindrical tube 16. This tube is disposed centrally within the casing 7 and serves as a support for a coiled tube 17. As here shown this tube comprises flat top and bottom walls 18 and 19, respectively, and its inner wall is formed by the tube 16. The outer wall of tube 17 contains a series of vertical louver elements 20 spaced apart to provide exit openings from the interior of the tube, as best shown in Figures 3 and 4. The top

wall 18 extends outwardly and supports from its outer edge a coiled apron 21, this apron being spaced from the tube a short distance and being in substantial concentric relation thereto.

The apron 21 contains a series of vertical openings 22 which are in substantial alignment with the louvers 20 in the peripheral surface of tube 17. It will be noted from an inspection of Figures 1 and 2 that the apron 21 has a depending lip 23 which extends downwardly beneath the bottom wall 19 of tube 17 and that the apron carries on its interior surface a series of curved spaced baffles 24. These baffles are attached to the apron 21 adjacent to the vertical openings 22 and are curved inwardly so that they tend to direct dust from the louvers 20, outwardly through the openings 22.

The tube 17 has a tangential inlet 25 disposed in substantially a horizontal plane so that gas entering the tube 17 passes in a horizontal direction and thence upwardly in a spiral path through this tube toward an exit 26 provided in the plate 15, and with which the extreme upper end of tube 17 connects. As the gas passes through this tube, the particles of dust are acted upon by centrifugal force and are thrown outwardly so as to pass through the louvers 20 and out into the space between these louvers and the apron 21. Upon entering this space, however, the particles encounter the deflecting baffles 24 which direct them either downwardly, so that they reach the dead space outside of apron 21, or pass through the openings 22 in this apron, from whence they fall by gravity into the hopper 10. The gas passes spirally upward through exit opening 26 and thence to tube 9.

In order to prevent dust from collecting on the top wall 18 of the inlet tube after its passage through the louvers 20, I provide a coiled inclined skirt 27 which is disposed beneath the louvers 20 and baffles 24. This skirt flares outwardly and is co-extensive with the bottom wall 19 of tube 17. Due to this structure any dust thrown out through louvers 20 and not having sufficient velocity to be carried through the openings 22 in the apron 21, will fall downwardly and be deflected by the skirt 100

27, from whence it will reach the dead space in casing 7 and fall to hopper 10 where it collects.

Dust arresters constructed in accordance 5 with my invention are particularly effective in that they contain no abrupt turns to obstruct the flow of air or gas, and yet are capable of removing practically all of the dust from heavily laden gas by a single traverse. 10 The perforated apron 21 prevents dust from being aspirated back into tube 17, after it has been thrown out into the dead space in casing 7.

I have shown the tube 17 as made up of 15 approximately two and one-half convolutions, but it will be clear to those skilled in the art that my invention is not limited to this number of turns, nor is it limited to the use of a coiled tube having a rectangular cross 20 section as shown, because other cross sections are equally suitable.

Although I have herein shown only one 25 form of centrifugal dust arrester embodying my invention, it will be obvious that various modifications may be made within the scope of the appended claims without departing from the spirit and scope of my invention.

What is claimed is:

1. A dust arrester comprising an upright 30 casing; a coiled tube mounted within and lengthwise of said casing, said tube having openings in its peripheral surface; and a coiled skirt disposed in inclined spaced relation to said tube beneath said openings.

35 2. A dust arrester comprising a hollow upright casing; a coiled tube disposed within said casing and lengthwise thereof, said tube having a series of louvers in its peripheral surface; and an inclined coiled skirt disposed 40 beneath said louvers and in spaced relation thereto.

3. A dust arrester comprising a hollow upright casing; a coiled tube disposed within said casing, said tube having a plurality of 45 openings in its peripheral surface; a perforated apron extending in approximately parallel relation to the peripheral surface of said tube; and a coiled skirt disposed beneath said tube and apron, and in inclined relation 50 thereto.

4. A dust arrester comprising an upright 55 casing; a coiled tube arranged to form a tortuous passageway lengthwise of said casing, said tube having louvers in its peripheral surface; a coiled apron extending in approximately parallel relation to the peripheral surface of said tube, and having openings therethrough; a series of baffles on the interior of said apron; and a spiral skirt disposed 60 beneath said tube and apron and inclined with respect thereto.

5. A centrifugal dust arrester comprising 65 an upright coiled tube having an inlet at the bottom and openings in its peripheral surface; a coiled apron concentric with said tube

and having openings therein; an inclined spiral skirt disposed beneath said tube and apron; and an upright casing enclosing all of said parts and providing a dust receiving chamber outside of said apron.

6. A centrifugal dust arrester comprising 70 an upright casing having a dust receiving space near its bottom end; a coiled tube disposed lengthwise within said casing and provided with a gas inlet near the bottom, and a gas outlet near the top, said tube having louvers in its peripheral surface; a coiled apron mounted in parallel spaced relation to said tube, and having openings therethrough; a series of upright baffles disposed on the interior of said apron for deflecting dust through the openings in said apron; and a downwardly inclined spiral skirt mounted below said tube and apron for deflecting dust into said casing.

7. A centrifugal dust arrester comprising 75 an upright casing; a coiled tube mounted within and lengthwise of said casing, and having a series of openings in its peripheral surface; a coiled apron disposed outside of 80 said tube and having openings in approximate alignment with the openings in said tube; and a series of upright baffles inside of said apron and extending substantially to the peripheral surface of said tube for deflecting 85 dust from said tube through the openings in said apron.

8. A dust arrester comprising an upright 90 casing; a coiled tube extending lengthwise of said casing and having an inlet adjacent the bottom and an outlet near the top, said tube having a series of slits in its peripheral surface; a coiled apron outside of said tube and spaced therefrom, said apron having 95 openings opposite the slits in said tube; a lip on said apron depending below said tube; and means for discharging dust collected in said casing.

9. A centrifugal dust arrester comprising 100 an upright casing with a dust discharging opening at the bottom; a spiral tube disposed in said casing and comprising a plurality of convolutions having louvers in the peripheral wall; a spiral apron disposed outside of said tube throughout its extent and having openings in it; and an inclined spiral skirt mounted below the louvers in said tube for deflecting dust into said casing.

In testimony whereof I have signed my name to this specification.

FREDERICK H. WAGNER.
